THOMAS L. DOWNEY, OF NEWARK, NEW JERSEY, ASSIGNOR TO WESTERN ELECTRIC COMPANY, INCORPORATED, OF NEW YORK, N. Y., A CORPORATION OF NEW YORK.

SYNCHRONIZING MECHANISM.

Application filed October 16, 1924. Serial No. 743,918.

This invention relates to talking moving picture machines and more particularly to a mechanism used in such machines for changing the relative position of the film record with respect to the sound record.

The object of this invention is to provide a synchronizing mechanism which will be efficient, cheap to manufacture and wherein the film record may be moved in synchronism with an associated sound record in a simple and positive manner.

A feature of the invention is to provide means adapted to be moved in operable relation with a gear reversing mechanism for imparting a relative movement to a film record with respect to an associated sound record in two directions.

Another feature is the provision of means whereby the film record is moved sequentially in synchronism with the sound record.

Another feature is the provision of means whereby a normally ineffective rotatable member is moved in position to cause the operation of a gear reversing mechanism a distance defined by the movement of the rotatable member.

Another feature is the provision of means whereby the gear reversing mechanism is caused to move an angular distance corresponding to the length of a picture on the film record.

Other features of invention and advantages will appear from the following description and by the claims appended thereto, reference being had to the accompanying drawings in which:

Fig. 1 is a partial assembly view of the synchronizing mechanism, and

Fig. 2 is a sectional view thereof taken approximately on line 2-2 of Fig. 1 and viewed in the direction indicated by the arrows.

The synchronizing mechanism shown in Fig. 1 consists of a driving shaft 10 to which a phonograph record (not shown) may be rotatably connected in any suitable manner. This shaft is journaled on bearings 34 and 35 formed integrally with the bracket 26. The pinions 11 and 12 are loosely mounted on shaft 10 and are each provided with a

toothed clutch portion 13 and 14 disposed in operable relation with clutch portions 15 and 16 with which they are respectively associated. The clutches 15 and 16 are slidably keyed on shaft 10 and are each provided with a forked lever 8 and 9 which are provided for moving them in and out of engagement from the clutches 13 and 14 through the operation of a mechanism that will be hereinafter described. Meshing with pinions 11 and 12 there is provided a pinion 17 which is rigidly secured on one end portion of a shaft 18. This shaft is rotatably mounted in bearing 36 and carries at its opposite end a spur gear 19 which meshes with gear 20. The gear 20 is securely mounted on one end portion of shaft 21 which is rotatably mounted in bearing 37 and carries at its opposite end a worm screw 22 disposed in operable relation with worm gear 23. This worm gear is securely attached to a housing 24 journaled on one end portion of the coaxially disposed shafts 10 and 25 and is provided for housing the differential mechanism D. M. shown in Fig. 1.

The shaft 25 is journaled in the upper portion of bracket 26 and carries at one end portion a bevel gear 28 which forms part of a differential mechanism, the function of which will be presently described. The other end of shaft 25 may be operatively connected to any well known type of moving picture machine, the picture film of which is to be brought in synchronism with a sound record which may be directly connected to the shaft 10. The differential mechanism D. M. generally consists of two beveled gears 27 and 28 rigidly secured on the adjacent end portions of shafts 10 and 25 respectively. Each of these gears meshes with two planetary gears 29 and 30 which are freely mounted on studs 31 and 32 secured to the housing 24.

Levers 8 and 9 are associated with cams 36 and 37 which are adapted for controlling the operation of clutches 15 and 16 respectively. Cam 37 is rigidly fastened on a rotatable shaft 38 which may be journaled in any suitable bearings (not shown). On one end portion of shaft 38 there is loosely

mounted a pinion 39 which meshes with gear 40 secured on the housing 24. This pinion has a toothed clutch portion 41 which engages a toothed clutch member 42 keyed on the shaft 38 and held in operable relation with the clutch portion 41 by means of a coil spring 43, which has one end portion in abutment with the collar 44. On the other end of shaft 38 there is freely mounted a toothed clutch member 45 with which a toothed clutch member 46 is held in operable relation by means of coil spring 47 which has one end portion in abutment with the collar 48. Lever 9 and the clutch 16 are normally held in a non-operated position by means of spring 53 which holds the roller 51 in the recess 49 of cam 37 as shown in Figs. 1 and 2. On the clutch member 45 there is securely mounted a handle member 55 adapted to impart a small angular movement to the cam shaft 38 for a purpose that will be herein-after described.

Similarly, the cam 36 is mounted on the rotatable shaft 56 which is supported and operable in the same manner as the shaft 38, it being sufficient to state for its operation that the toothed clutch members 57, 58, 59 and 60 carried thereby are made effective in a direction opposite the corresponding clutch members 45, 46, 42 and 41 on shaft 38. The handle levers 61 and 55 are each held in normal non-operative positions against the stops 62 and 63 by means of their respective associated springs 64 and 65, shown in Fig. 2.

The operation of the synchronizing device is as follows:

Supposing that the shaft 10 rotates in a counter clockwise direction as indicated by the arrow, the shaft 25 is obviously rotated in a clockwise direction through the differential mechanism D. M. which as stated above includes the bevel gears 27, 28 and planetary gears 29 and 30. Supposing that it is necessary to move the picture record in synchronism with the sound record or in other words to change the relative position of shaft 25 with respect to shaft 10, the handle lever 55, for example, is moved into the position indicated by the dotted line shown in Fig. 2, against the resistance of retracting spring 65. The movement of handle lever 55 and the toothed clutch 45 in operable relation with its associated clutch portion 46, rotates the shaft 38 and the cam 37 carried thereby, a small angular distance. The movement of cam 37 moves the lever 9 and the continuously driving clutch 16 in operable relation with the toothed clutch portion 14 of pinion 12. Pinion 12 is then rotated in the direction of the driving shaft 10, which in turn rotates the pinion 17 and the gear 19 in the direction indicated by the arrow. Gear 19 transmits its movement to gear 20, which in turn,

rotates the housing 24 and the planetary gears 29 and 30 carried thereby in a clockwise direction through the movement of worm 22 in operable relation with worm gear 23. While the housing is rotated, pinion 27 performs the function of a rack for planetary gears 29 and 30 which change the relative position of shaft 25 with respect to shaft 10 by advancing the shaft 25 an angular distance equal to twice the movement of housing 24.

The spur gear 40 carried by the housing 24, rotates the pinion 39 which through its engagement with the toothed clutch member 42 keyed on the shaft 38 rotates the cam 37 until the recess 49 of the cam registers with roller 51 of lever 9 where clutch 16 is disconnected from the tooth portion of pinion 12 through the action of retracting spring 53 thus limiting the angular movement of housing 24 and the relative movement of the shaft 25 with respect to the shaft 10. The lever 55 is returned to its normal position by means of retracting spring 65.

It is obvious that by moving the clutch 15 in operable relation with the toothed clutch member 13 of pinion 11, the direction of movement of housing 24 and shaft 25 will thereby be reversed and operated in the same manner as already described for shaft 38. For this reason, it is not thought necessary to explain further the operation of this part of the synchronizing mechanism.

What is claimed is:

1. In a synchronizing mechanism, a driven shaft, a driving shaft, a gear reversing mechanism, a pair of independently operable clutches mounted on said driving shaft for actuating said reversing mechanism and a differential mechanism actuated by said reversing mechanism for changing the relative position of said driven shaft with respect to said driving shaft.

2. In a synchronizing mechanism, a driven and driving shaft, a gear reversing mechanism mounted on one of said shafts, a differential mechanism actuated by said gear reversing mechanism for changing the relative position of said shafts, and means comprising cam shafts, operated by the movement of the differential, and a plurality of levers for controlling the relative angular movement of said shafts.

3. In a synchronizing mechanism, a driven shaft, a driving shaft, a connection between said driving and driven shafts, one set of means cooperating with the connection for advancing the rotation of one of said shafts relative to the other and a second set of means for retarding the rotation of one of said shafts relative to the other and automatically operable means in each set of advancing and retarding means for limiting the extent of the relative movements.

4. In a synchronizing mechanism for talking moving picture machines, the combination of driven and driving shafts, shaft and pinion gears connecting the driven and driving shafts, a housing enclosing the shaft and pinion gears, a plurality of clutch members slidably keyed to the driving shaft, a plurality of loose pinion gears, journaled on the driving shaft, cam shafts, a gear connection between the housing and the cam shafts, clutch shifting levers operating from the cam shafts to shift the clutch members into engagement with the loose pinion gears, a set of gears to carry movement of the loose pinion gears to the connection between the driving and driven shafts and move the housing enclosing the shaft and pinion gears and cause movement of the driven shaft with respect to the driving shaft as defined by the extent of movement of the cam shafts.

5. In a synchronizing mechanism for talking moving picture machines, driving and driven shafts, a differential mechanism for coupling said shafts, a housing enclosing the differential mechanism, a normally ineffective gear reversing mechanism carried by the driving shaft, cam shafts, a gear connection between the housing and the cam shafts, levers operating from the cam shafts to bring the gear reversing mechanism into operation, a gear connection between the gear reversing mechanism and the said differential mechanism to impart movement to the differential gear housing and to the driven shaft relative to movement of the driving shaft to a degree defined by extent of movement of the cam shafts.

6. In a synchronizing mechanism for talking moving picture machines, driving and driven shafts, a differential mechanism for coupling said shafts, a housing enclosing the differential mechanism, normally ineffective gear changing mechanism carried by the driving shaft, a gear connection between the gear changing mechanism and the said differential housing, cam shafts, a gear connection between the cam shafts and the differential housing, lever arms from the cam shafts to the gear changing mechanism to bring the gear changing mechanism into operation to transmit motion of the driving shaft to the differential housing and to change the speed of rotation of the driven shaft with respect to the driving shaft; and manually operable clutches to rotate the cam shafts and predetermine the distance the cam shafts will rotate under the power transmitted to them through the gear connection between the differential housing and the cam shafts.

7. In a synchronizing mechanism, the combination of a driving and a driven shaft, a differential mechanism for coupling said shafts, a normally ineffective mechanism for actuating said differential to impart a relative

advance movement to said driven shaft with respect to said driving shaft, and a normally ineffective mechanism for actuating said differential to decrease the velocity of said driven shaft with respect to said driving shaft, separate means for each of the normally ineffective mechanisms to render each of the mechanisms effective, and automatic means separate for each of said normally ineffective mechanisms for controlling the effective movement of each of said normally ineffective mechanisms.

8. In a synchronizing mechanism, continuously rotating driving and driven shafts, a normally ineffective gear train associated with said driven shaft, cam shafts, and manually operable means carried by each of said cam shafts for causing the movement of said gear train for increasing or decreasing the velocity of said driven shaft with respect to said driving shaft.

9. In a synchronizing mechanism, a driving shaft, a driven shaft loosely connected to said driving shaft, gear mechanism rotatably supported on said driving shaft and normally ineffective with respect to said driven shaft, a plurality of clutch members associated with said gear mechanism, and means individual to each of said clutch members for moving said clutch members for causing the operation of said gear mechanism for changing the position of said driven shaft with respect to said driving shaft in directions defined by said means.

10. In a synchronizing mechanism, the combination of driving and driven shafts, a gear train normally ineffective with respect to said driven shaft, clutch members associated with said gear train and rotating with said driving shaft, mechanism individual to each of said clutch members for moving each of said clutch members in position to render said gear train effective with respect to said driven shaft, and means individual to each of said clutch members operable for controlling the effective movement of said gear train to impart a limited relative movement to said driven shaft with respect to said driving shaft.

11. In a synchronizing mechanism, the combination of driving and driven shafts, a gear reversing mechanism associated with said driving shaft and normally ineffective with respect to said driven shaft, a pair of clutch members carried by said driving shaft and arranged to be moved in and out of engagement from said gear reversing mechanism, cam shaft mechanism therefor including rotatable shafts, a cam carried by each of said shafts, forked levers engaging said clutches and said cams, manually operable means for imparting a preliminary angular movement to one of said shafts to bring one of said clutch members into engagement with said gear reversing mechanism for causing

an advance movement of said driven shaft of said driven shaft, and indented portions with respect to said driving shaft, manually on said cams for limiting the advance and operable means for imparting a preliminary reverse movements of said driven shaft. 10
angular movement to the other of said shafts In witness whereof, I hereunto subscribe
5 to bring the other of said clutch members my name this 10th day of October, A. D.,
into engagement with said gear reversing 1924.
mechanism for causing a reverse movement
